UNITED STATES PATENT OFFICE.

FREDRIC W. YEO AND ALFRED J. BOHL, OF MILWAUKEE, WISCONSIN.

SAFETY FARE-BOX FOR STREET-CARS.

1,063,758.

Specification of Letters Patent.

Patented June 3, 1913.

Application filed September 13, 1911. Serial No. 649,207.

To all whom it may concern:

Be it known that we, FREDRIC W. YEO and ALFRED J. BOHL, citizens of the United States, residing at Milwaukee, county of Milwaukee, and State of Wisconsin, have invented new and useful Improvements in Safety Fare-Boxes for Street-Cars, of which the following is a specification.

Our invention relates to improvements 10 in fare boxes.

The object of our invention is to provide a form of box adapted to serve either as a stationary or as a portable box and which will readily receive cash fares consisting of 15 coins of any size, fare checks and ordinary ticket fares, but will prevent fraudulent withdrawals.

In the drawings—Figure 1 is a side elevation of our improved fare box. Fig. 2 20 is a vertical sectional view of the same, drawn on line α — α of Fig. 1. Fig. 3 is a front elevation. Fig. 4 is a plan view of the till or lower portion of the box. Fig. 5 is a detail view of a set of gravity fingers.

25 Like parts are identified by the same reference characters throughout the several views.

Our improved box comprises a receptacle, 30 preferably rectangular in form, the vertical dimension being greatest. It is divided horizontally into two compartments by a horizontal partition 1 having a large opening therethrough, normally closed by a swinging trap lid 2 hinged to the partition wall by a pintle 3, which projects through one side wall 4 of the box and is provided with a handle 5, whereby the lid 2 may be swung. The upper compartment 6 receives the fares initially through a slot 7 in the top 8 and 35 the lower compartment 9 serves as a till. The front wall 10 is preferably provided with a sight glass 11 through which the fares may be observed when resting upon the lid before delivery into the till, and a 40 similar sight glass may be provided in the rear wall. The upper compartment is provided with a series of slides or inclined walls partially obstructing the passage of the fares through the compartment from the slot 7 to 45 the lid 2.

A receiving chamber 13 is formed by ver-

tical walls 14 and 15, and inclined walls 16 and 17, which cross the upper compartment 6 from front to rear with sufficient space between the lower margins of the converging walls 16 and 17 to permit the fares to freely pass through without danger of clogging. Within the receiving chamber and directly below the slot, a baffle composed of angularly divergent walls 20 and 21 is provided. 55 These walls meet at their upper margins and diverge downwardly, preferably in the direction of the angles formed by the chamber walls 14 and 15 with the inclined walls 16 and 17. The fares will therefore pass through the slot 7 and be deflected outwardly toward one side or the other by this two way baffle, and on passing the baffle, 60 will be again deflected inwardly to the opening 25 between the walls 16 and 17, which 65 is located directly underneath the baffle. A second baffle of similar form is located below the opening 25, and comprises the downwardly and laterally diverging walls 26 and 27. The lower margins of these walls 70 approach the side walls 4 and 28 respectively, and deliver the fares to slides 30, which project inwardly and downwardly from such walls. Rods 31 and 32 cross the compartment from front to rear underneath 75 the walls 26 and 27 and gravity actuated retaining fingers 35, pivotally supported by the rods 31, are adapted to swing laterally 80 into contact with the lower margins of the slides 30, thus substantially spanning the 85 gaps 36 between the slides 30 and the baffle walls 26 and 27. The rods 32 are below rods 31 and serve as stops to limit the movement 90 of the fingers in the opposite direction to prevent them from swinging across a vertical plane through their supporting rod 31, the term "vertical" being used on the assumption that the box is in an upright position.

It will be observed that the walls 16 and 17 of the receiving chamber 13 and also the slides 30 constitute inwardly directing baffles. A fare dropped through the slot 7 will be deflected by one of the baffles 20 or 21 95 outwardly and immediately thereafter will 100 be turned inwardly by the baffle wall 16 or 17. On passing through the opening 25, the

fare will again be deflected outwardly by the baffle wall 26 or 27, and then inwardly by one of the baffles or slides 30, and will drop therefrom to the partition between compartments 6 and 9. This of course assumes that the fare box is in its normal vertical position, or substantially in such position. The fingers 35 in normal position will rest against the stop rods 32 and will direct 10 the fares delivered from the slides 30 downwardly with a slight outward inclination. The fares, whether in the form of cash, checks, or tickets will have been turned by the baffles and the fingers 35 to such a position that their lower marginal edges will strike on the partition or near the side margin of the lid 2, whereupon the fare will fall to a horizontal position upon the lid, the fixed portion of the partition constituting 15 merely a narrow ledge. After the fare has been inspected through the sight opening 11, lever 5 may be actuated to tilt the lid and discharge the fares into the till 9. The front wall of the till is provided with a door 37, as shown in Fig. 3, which door is kept normally locked, a lock being illustrated at 38.

Owing to the fact that two sets of outwardly and inwardly projecting baffles or walls are employed within the compartments 6, it is obvious that it is impossible for any tool to be manipulated through the slot 7 into a position where it can interfere with the operation of the fingers 35. The lower baffle walls 26 and 27 effectually 20 protect the fingers 35 from interference, and are adapted particularly to prevent access to the pivot rods 31. Each of the fingers being free to swing independently of the other, it is obvious that any obstruction 25 which may be dropped through the slot 7 will obstruct the escape of the fares to the same extent that it interferes with the movement of the fingers. It is also obvious that any attempt to tilt the fare box to one side 30 or the other, or to invert it for the purpose of shaking fares out, will be futile, since the fingers 35 will in such case fall by gravity to the dotted line position indicated in Fig. 2 and prevent the fares from passing 35 through the gap between the baffle walls 26 and 27 and the baffles or slides 30.

Our improved fare box is preferably formed in sections, the upper section being open at the bottom and forming the compartment 6. Lugs 38 are provided in each corner for securing the upper section or compartment to the lower section, said lugs overlapping the corner portions of the partition 1 and being secured by screws or bolts 40 39, which may be inserted from beneath when the door 37 is open. This makes it possible to secure access to the upper section by removing the fastenings which connect the lugs with the partition 1. The glass 45 windows or sight glass members 11 are pref-

erably inserted from below in retaining grooves 40 formed in the walls of the upper compartment or section. These glass windows may be so inserted when the upper section is separated from the lower one. If 70 desired, springs 41 may be employed to hold the lid 2 in its normal horizontal position. This lid, when in horizontal position, strikes against the fixed portion of the partition 1, which prevents it from moving into compartment 6. 75

We claim—

1. A fare box consisting of the combination with a till, having an upper wall partially composed of a swinging lid, a receiving compartment mounted upon the till and provided with a slot in its upper wall, two sets of outwardly and inwardly deflecting baffles located in the receiving compartment, and swinging fingers pivotally supported underneath the lower outwardly deflecting baffles in a position to swing by gravity into engagement with the lower inwardly deflecting baffles, substantially as 85 described. 90

2. A fare box consisting of the combination with a till, having an upper wall partially composed of a swinging lid, a receiving compartment mounted upon the till and provided with a slot in its upper wall, two sets of outwardly and inwardly deflecting baffles located in the receiving compartment, and swinging fingers pivotally supported underneath the lower outwardly deflecting baffles in a position to swing by gravity into engagement with the lower inwardly deflecting baffles, substantially as described, together with stop rods limiting the inwardly swinging movement of the fingers. 95 100

3. The combination with a till, of a flare receiving compartment mounted thereon and provided with a slot in its upper wall, a fare receiving chamber having its walls suspended from the upper wall of said compartment and having a partially closed bottom composed of downwardly and angularly inclined baffle walls, a two way baffle in said receiving chamber located underneath said slot and provided with downwardly and outwardly inclined walls, a second two way baffle in the lower portion of said compartment underneath the opening in the bottom of the receiving chamber, and a set of retaining fingers pivotally supported underneath said last mentioned baffle and adapted to prevent the return of fares from the lower portion of the compartment to a position above such baffle, and manually operated means for discharging fares from the lower portion of said compartment into 110 115 the till. 120

4. The combination with a fare receiving till having its top composed in part of a swinging lid, of a fare receiving compartment provided with an open bottom and de- 130

tachably mounted upon said till, said receiving compartment having a slot in its upper wall, means for securing the upper compartment to the till from within the till, a sight glass mounted in slide bearings in the upper compartment and movable into engagement with said bearings from the open lower end thereof, said sight glass being retained in

position by the till when the receiving compartment is secured thereto.
